[57] CLAIM

The ornamental design for a game carrier, as shown and described.

DESCRIPTION

FIG. 1 is a front perspective view of a game carrier showing my new design;

FIG. 2 is a front elevational view thereof, the rear being a mirror image of the front shown in FIG. 2;

FIG. 3 is an end elevational view thereof;

FIG. 4 is an end elevational view thereof;

FIG. 5 is a top plan view thereof; and,

FIG. 6 is a bottom view thereof.

FIG. 1

FIG. 2

FIG. 3

FIG. 4

FIG. 5

FIG. 6
